Specification for Design.

Patented Sept. 12, 1916.

Application filed January 25, 1916. Serial No. 74,271. Term of patent 14 years.

To all whom it may concern:

Be it known that I, HENRY PRICE BALL, a citizen of the United States, resident of borough of Brooklyn, county of Kings, city and State of New York, have invented a new, original, and ornamental Design for a Lamp, (Case A,) of which the following is a specification, reference being had to the accompanying drawings, forming a part hereof.

In the drawings, Figure 1 is a plan view; Fig. 2 is a side elevation, and Fig. 3 is a bottom view of my new design for a lamp.

The design comprises a body of generally

cylindrical shape having three longitudinal grooves extending from the bottom but terminating below the top of the body. The upper part of the body is cylindrical.

I claim:

The ornamental design for a lamp, substantially as shown and described.

This specification signed and witnessed this 20th day of January, 1916.

HENRY PRICE BALL.
